UNITED STATES PATENT OFFICE.

GORDON B. FIELDS, OF JACKSONVILLE, FLORIDA.

TYPE-SLUG-CASTING APPARATUS.

Application filed March 24, 1922. Serial No. 546,446.

To all whom it may concern:

Be it known that I, GORDON B. FIELDS, a citizen of the United States, residing at Jacksonville, in the county of Duval and State of Florida, have invented new and useful Improvements in Type-Slug-Casting Apparatus, of which the following is a specification.

This invention relates to the art of printing and has for an object the provision of means for reproducing or duplicating type, zinc etchings, such as autographs and the like, the invention being especially designed for the latter.

Another object of the invention is the provision of a simple and improved method of casting or reproducing zinc etchings or type in slug form, by the use of a type casting machine, the invention being especially useful in printing signatures upon bond coupons. As an illustration, in printing a number of signatures upon the coupons of a single bond, the latter must be run through the press a number of times, or a separate etching, mounted and inserted in type form, must be supplied for each coupon signature.

Both of these methods are expensive, while by the use of the present invention, any number of duplicates can be made from a single zinc etching by a linotype operator, at a low cost and in a relatively short time.

With the above and other objects in view, the invention further includes the following novel features and details of construction, to be hereinafter more fully described, illustrated in the accompanying drawings and pointed out in the appended claims.

In the drawings:—

Figure 1 is a detail perspective view of a bench vise etching holder or depth block, used in connection with the invention.

Figure 2 is an elevation of the same showing a zinc etching attached thereto.

Figure 3 is a detail perspective view of a blank matrix slide.

Figure 4 is an elevation of a casting block with the matrix slide in place.

Figure 5 is an end view showing the parts assembled for insertion in a bench vise.

Figure 6 is an elevation of the casting block after it is removed from the bench vise and showing the matrix etching within the matrix slide.

Figure 7 is a detail view of a slug reproduced upon the matrix slide.

Figure 8 is an elevation of this slug.

Figure 9 is an elevation of a bench vise type holder showing the type in place.

Figure 10 is a view similar to Figure 5 showing the type holder substituted for the etching holder.

Referring in detail to the drawings, wherein like characters of reference denote corresponding parts, the invention comprises a bench vise etching holder and depth block which is indicated at 15. This holder is provided along one face with a depression or groove 16, within which is adapted to be seated a zinc etching to be reproduced, herein shown as a signature and indicated at 17. 70 This etching is in unmounted form and its lower side is cleaned and pasted to the bench vise etching holder within the groove 16, as illustrated in Figure 2 of the drawings.

A matrix slide which is indicated at 18 is 75 next positioned within a type casting machine casting block 19 and the holder 15 and block 19, together with a bench vise filling piece 20 is inserted in a bench vise and pressure is applied until the etching holder and casting block are pressed firmly together at the points indicated at *a* and *b*. The zinc etching 17 is then forced into the matrix slide, the depth being regulated by the contact of the etching holder and casting block 80 at the points *a* and *b* and provides a proper depth for casting a slug type high. 85

The etching holder and casting block are then removed from the bench vise and the zinc etching removed from the matrix slide, 90 care being exercised so as not to injure the matrix.

The casting block with the matrix slide therein is then inserted in a linotype machine, the metal in the pot of this machine 95 being worked at as low a temperature as possible without producing a chilled slug. A slug produced from this matrix is indicated at 21. By brushing the matrix in the casting block for each casting with a suitable 100 brush, such as a tooth brush and by using graphite, as many slugs may be produced as are needed.

In addition to the reproduction of zinc etchings, the invention is also capable of use 105 in duplicating type. In the latter use, pure lead should be used as a matrix material and a bench vise type holder such as indicated at 22 and shown in Figure 9 of the drawings should be substituted for the 110

bench vise etching holder and depth block. The type is set up within the holder 22 and the latter is arranged as shown in Figure 10 and placed within a bench vise. Pressure is applied and the method described in connection with the reproduction of etchings, is followed.

The invention is susceptible of various changes in its form, proportions and minor 10 details of construction and the right is here- in reserved to make such changes as prop- erly fall within the scope of the appended claims.

Having described the invention what is 15 claimed is:—

1. The herein described method of forming matrices for type casting machines consisting of a type carrying block having a shoulder arranged above and below the type 20 and the casting block having a matrix slide therein, the type of the type carrying block being positioned in contact with the slide; and then subjected to pressure to force the type into the slide, until the shoulders of 25 the type carrying block engage the face of

the casting block to form a matrix for use in type casting machines.

2. The herein described method of forming matrices for type casting machines consisting of a combined etching holder and 30 depth regulating block, having an etching secured thereto and a casting block having a matrix slide in one face thereof and a filling piece in the opposite face, with the etching arranged in contact with the 35 slide; and then subjecting the block to pressure to force the etching into the face of the slide to a depth regulated by the combined holder and depth block, to form a matrix for use in type casting machines.

3. Means for making matrices comprising a casting block, a matrix slide therein, a combined holder and depth regulator for holding an etching or type, for contact with the matrix slide and a filling piece for the 45 casting block, whereby the block and holder may be subjected to pressure to force the etching or type into the face of the slide.

In testimony whereof I affix my signature.
GORDON B. FIELDS.
